(57) CLAIM

The ornamental design for a commode seat, as shown and described.

DESCRIPTION

FIG. 1 is a front perspective view of a commode seat showing our new design thereof;

FIG. 2 is a top view thereof;

FIG. 3 is a bottom view thereof;

FIG. 4 is a front view thereof;

FIG. 5 is a back view thereof;

FIG. 6 is a side view of the right side thereof;

FIG. 7 is a side view of the left side thereof; and,

FIG. 8 is a front-left perspective view thereof positioned on an exemplary commode.

The broken lines and the dotted lines shown in the drawings are directed to environment, are for informational purposes only, and form no part of the claimed design.

The bold, wavy lines do not constitute a feature of the design. They are included for illustrative purposes only in order to define the boundary of the design.

The lines parallel to an axis running from the front of the commode seat to the back of the commode seat and on the back of the commode seat shown in FIG. 5 are included to show curvature of the commode seat.

It is recognized that the inventive aspects of the current design exist in the commode seat as a whole, in all individual portions and elements thereof, and in all combinations of portions and elements thereof. Applicant reserves the right to amend this application and/or to file one or more divisional and/or continuation applications to specifically claim the commode seat as a whole, to specifically claim individual portions or elements thereof, and/or to specifically claim combinations of portions and elements thereof.
